ABSTRACT

An improved gold pan in which a riffle is integrally formed in the sloping side wall of the pan with the riffle spiraling downwardly and inwardly from a point adjacent the rim to a point adjacent the edge of the flat bottom portion of the pan. The riffle has a pronounced overhang on its lower edge to catch and hold back the heavy gold dust nuggets while permitting the overburden, (i.e., rocks, large grains of sand, etc.). The pan is used in a conventional manner by the miner.

GOLD PAN**BACKGROUND OF THE INVENTION****FIELD OF THE INVENTION**

The present invention relates to gold pans used by a miner to separate gold dust and nuggets from rocks and sand.

SUMMARY OF THE INVENTION

The improved gold pan of the present invention has a circular flat bottom wall and a relatively long upwardly and outwardly sloping side wall extending integrally upwardly from the bottom wall. A riffle extends spirally inwardly and downwardly from the outer edge of the side wall to peripheral edge of the bottom wall. The riffle has a curved overhang opening toward the center of the pan to catch and hold the heavier gold dust or nuggets during the panning of gold. The overburden of rock and sand is permitted to escape the pan while the gold is retained therein.

The primary object of the invention is to provide a gold pan having a gold retaining riffle formed therein.

Other objects and advantages will become apparent in the following specification when considered in light of the attached drawings.

BRIEF DESCRIPTION OF THE DRAWINGS

FIG. 1 is a top plan view of the invention;

FIG. 2 is a vertical sectional view, taken along the line 2—2 of FIG. 1, looking in the direction of the arrows; and

FIG. 3 is a vertical sectional view, taken along the line 3—3 of FIG. 2, looking in the direction of the arrows.

DESCRIPTION OF THE PREFERRED EMBODIMENT

Referring now to the drawings in detail, wherein like reference characters indicate like parts throughout the several figures, the reference numeral 10 indicates generally an improved gold pan constructed in accordance with the invention.

The improved gold pan 10 is normally formed integrally of metal and includes a circular flat bottom wall 11 and an upwardly and outwardly sloping side wall 12 integrally extending from the peripheral edge of the flat bottom wall 11. The side wall 12 has an outer peripheral edge 13 which forms the edge of the gold pan 10. The side wall 12 is thickened at 14 to form a riffle 15

which extends spirally inwardly and downwardly from the peripheral edge 13 of the side wall 12 to the peripheral edge 16 of the bottom wall 11. The riffle 15 is undercut at 17 opening toward the center of the gold pan 10.

In the use and operation of the invention a miner will scoop up a pan full of material from the bottom of a stream and while still holding it under water gently shake it to and fro with the riffle portion facing the front of the pan. This action will dislodge rocks and large grain sand without loosing the gold dust or nuggets which are retained in the pan by the riffle. In other instances miners will manipulate the pan in a circular motion with the effect being the same. In other instances the pan is brought up out of the water and manipulated completely out of the water with the result again being the same.

The riffle is illustrated in the drawings particularly in FIG. 1 as spiraling inwardly and downwardly in a counter clockwise direction and it should be understood that the direction of the riffle can be reversed to a clockwise direction if desired. In practical use of the gold pan of the instant invention a considerable greater quantity of gold was recovered then when using an ordinary pan since all of the gold was retained in the pan of the invention.

Having thus described the preferred embodiment of the invention it should be understood that numerous structural modifications and adaptations may be resorted to without departing from the spirit of the invention.

What is claimed is:

1. In a gold pan, a circular generally flat bottom wall and an upwardly and outwardly sloping side wall integrally secured to the bottom wall along the peripheral edge thereof, said side wall having an outer peripheral edge, a deep spiral riffle integrally formed in said side wall and extending spirally inwardly and downwardly from points adjacent the peripheral edge of said side wall to a point adjacent the peripheral edge of said bottom wall, and said riffle having an overhang opening toward the center of the gold pan, said riffle being formed by a portion of the side wall that is of gradually increasing thickness adjacent said riffle.

2. A device as claimed in claim 1 wherein the major portion of the riffle is spaced inwardly and away from the outer peripheral edge of the side wall so that the riffle has a non-parallel relationship to the outer peripheral edge of the side wall.
